UNITED STATES PATENT OFFICE.

RALPH GRAY, OF FAYETTE CITY, PENNSYLVANIA.

MACHINERY FOR HANDLING BLOW-PIPES IN GLASS-WORKING.

SPECIFICATION forming part of Letters Patent No. 223,726, dated January 20, 1880.

Application filed September 15, 1879.

To all whom it may concern:

Be it known that I, RALPH GRAY, of Fayette City, in the county of Fayette and State of Pennsylvania, have invented certain new and useful Improvements in Machinery for Handling Blow-Pipes in the Manufacture of Blown Glass; and I do hereby declare the following to be a full, clear, and exact description of the invention, such as will enable others skilled in the art to which it pertains to make and use it, reference being had to the accompanying drawings, which form part of this specification, and in which—

Figure 1 is a side elevation of the apparatus complete. Fig. 2 is a plan view of the device for supporting the blow-pipe. Fig. 3 is a longitudinal section of part of the same. Figs. 4 and 5 are details.

This invention relates to devices for taking the weight off of the operator in making cylinders of glass, so that he can make larger sizes than are now possible, and with but little labor.

My invention consists in the novel construction, combination, and arrangement of devices, as hereinafter described and specifically claimed.

I construct an elevated railway, A, at a suitable height, and running from either the melting or warming-in furnace straight outwardly. Upon this railway rides a truck, B, from which projects downwardly a rigid hanger, C, or bracket. A catch, a, projects from the truck B, which is held in position by a spring, and is provided with an operating handle or cord, b, extending down within reach of the operator. A stop, D, having a cushioning-spring, s, is set above the track, consisting of a rod having the inclined lug e and the stud d, both in the track of the catch a.

When the gather or ball is run back from the furnace the proper distance, catch a runs past lug e and is caught between it and stud d, thus retaining the truck B and hanger C in a fixed position. To release them in order to approach the furnace, the handle b is pulled and the catch a is disengaged.

Through a bearing in the lower end of hanger C passes a shaft, e, to which is rigidly attached an arm, f, having a sliding counter-weight, E,

provided with any ordinary means of adjustment to any desired radius. On shaft e, at the other side of hanger C, is fixed a bar, F, whose main portion g projects in a direction opposite that of arm f, but has a portion, h, 55 projecting in the same direction. At the end of portion h of bar F are two holes, and in these slide pins i i, which carry a slotted or bifurcated frame, G, in each of the legs of which are set two friction-rollers, k k, as shown. 60

The upper part of the blow-pipe is inserted in the slot by forcing it between the two opposite rollers; or one of them may have a yielding bearing. The rollers then permit the rotation of the blow-pipe, and the pins i i permit it to be moved laterally while rotating.

The lower end of the blow-pipe is held as follows: It has near the bottom a round collar, l. Projecting from the end of part g of the arm F, similarly to frame G, is a frame, H, in two parts, hinged together at the outer end, and each cut away to form a central opening when closed together. The suspending-arm m of frame H is rounded, as is the projection n of its swinging half, and a sliding sleeve, p, 75 locks the two together.

Sleeve p is operated by lever q and arm r, as shown, and may be fitted with a spring to force it into locking position for convenience.

Frame H has three or more grooved rollers, 80 t, set so as to bear upon the collar l of the blow-pipe when inserted, thus allowing free rotation while preventing any endwise movement of the pipe.

The whole apparatus is ranged along and 85 partly suspended over the pit, and at such a height that when a cylinder or ball is swinging vertically in the pit the mouth-piece will be in convenient position for blowing while manipulating.

The devices are used as follows: I will suppose the gathering to be done. The weight of the pipe and ball are known, and the counter-weight E is adjusted so as to balance as nearly as possible the combined weight of the swinging devices, the pipe, and the ball. Lever q is worked to release the frame H, which is then opened and collar l of pipe inserted, the frame shut and locked, and the upper part of pipe is inserted in frame G. The workman has no 90 95 100

weight to carry at all, and no muscular effort to make, except to overcome the inertia of the apparatus. The rolling truck enables him to easily push the ball into the warming-in furnace and draw it out, after which he causes the catch *a* to secure the whole, when he is free to manipulate the ball into a cylinder. Shaft *e* allows swinging in a vertical plane to lower into the pit or throw aloft. Pins *i* permit a lateral movement of the pipe and the truck longitudinal movement to allow the thrust sometimes necessary to shape the cylinder.

I am thus able to give the glass any of the motions required for successful manipulation, and during any one of them I can readily rotate the ball or cylinder. It is therefore obvious that much arduous labor is avoided; and since the weight is adjustably countered I can easily handle weights of fifty, seventy-five, or one hundred pounds, or more—a result which is practically impossible of accomplishment by the hand process.

What I claim as my invention is—

1. An apparatus adapted to support the blow-pipe and ball or gather in glass-working, journaled horizontally, and provided with retaining-clasps to carry the pipe and an adjustable counter-balance on the side of the journal opposite said ball or gather, as set forth. 25

2. The combination, with ways *A* and truck *B*, of the cushioned stop *D*, having lugs *c* and stud *d*, and the spring-catch *a*, substantially as set forth. 30

3. The combination, with the bar *F*, sliding sleeve *p*, suspending-arm *m*, and projection *n*, of the lever *q*, substantially as described and shown. 35

4. The combination, with the bifurcated frame *G*, pins *i*, and bar *F*, of the lever *q*, substantially as described. 40

In testimony that I claim the foregoing I have hereunto set my hand this 25th day of August, 1879.

RALPH GRAY.
